UNITED STATES PATENT OFFICE.

WILLIAM GOLDMAN, OF BROOKLYN, NEW YORK.

WATER-FEED MEANS FOR CLOTHES STEAMING AND PRESSING APPARATUS.

Application filed January 31, 1924. Serial No. 689,833.

To all whom it may concern:

Be it known that I, WILLIAM GOLDMAN, a citizen of the United States, and a resident of the borough of Brooklyn, county of 5 Kings, city and State of New York, have invented certain new and useful Improvements in Water-Feed Means for Clothes Steaming and Pressing Apparatus, of which the following is a specification, sufficient to

enable others skilled in the art to which the invention appertains to utilize the same.

My present invention is supplementary to that set forth in my concurrent application Serial No. 534,818, filed February 7th, 1922 15 and like that relates to new and advantageous method of, and means for, feeding water to the steam generators used in conjunction with clothes steaming and pressing apparatus, whereby the operation may be 20 accomplished in a manner substantially automatic with a saving in both time and labor, and also much more effectively and economically as to results, as compared with the prior state of the art. Heretofore the 25 feed water has been pumped into the steam generators of such clothes pressing apparatus by hand, in a way both crude and unsatisfactory, owing to the time and labor involved, and to the fact that such feed re- 30 placement water was fed in a relatively cold condition into said generator, thereby retarding and delaying the operativeness of the apparatus, considered in a unitary sense, and impairing its utility and output, where- 35 as by my improvements I am enabled to render the available operativeness of the pressing and steaming mechanism essentially continuous and uniform in character.

Hence, my present invention consists in 40 the specific combination and arrangement of devices and appurtenances hereinafter described and claimed, whereby the water feed is rendered positively automatic by electrical means in conjunction with water level float- 45 controlled switch mechanism substantially as set forth,—a distinctive feature being the utilization of an electric motor for the purpose of actuating the valves of the feed water system, thereby eliminating the necessity for manual control, and rendering the 50 water feed operation practically intermittently continuous as long as the apparatus is used.

In the accompanying drawings, I exemplify a practical embodiment of the essen-

tial features of my invention, although I do not limit myself to the identical construction and configuration of parts and appurtenances described and claimed, since modifications in minor details, and equivalent mechanical expedients, may be resorted to with like results, and without departing from the spirit and intent of my invention in this respect.

With this understanding:—

Fig. 1, is a view, more or less diagrammatic, illustrating a practical embodiment of my invention as related to the steam generator of a cloth moistening and pressing apparatus of well known type in the art, 70 said steaming and pressing means being indicated by dotted lines;

Fig. 2, is an elevation of my feed water tank and appurtenances, the pipes connecting it with the steam generator being broken 75 away in part;

Fig. 3, is a central vertical section of said feed water tank, taken at right angles to Fig. 2, showing the adjunctive parts in sectional elevation;

Fig. 4, is a top view of the feed tank and connections;

Fig. 5, is an elevation of one of the feed valves, showing the stem, etc., in partial section;

Fig. 6, is a sectional detail of the means for actuating the coupling bar by which the valves are simultaneously opened and closed, as hereinafter set forth;

Fig. 7, is a sectional elevation showing in detail the float mechanism for controlling the valve actuating electric motor current;

Fig. 8, is a section taken upon plane of line 8—8, Fig. 7;

Fig. 9, is a diagrammatic representation 95 of the electric motor circuit by which the feed valves are actuated.

In Fig. 1, the cloth steaming and pressing apparatus is indicated by the dotted lines A, the same being connected up in the usual 100 manner with a steam generator boiler B, and the said apparatus and boiler functioning conjunctively in a manner heretofore well known in the prior state of the art.

The boiler B, is provided at its lower 105 extremity with a powerful heating element H, of any usual or appropriate character, adapted to generate steam rapidly, which steam is supplied to the clothes steaming and pressing apparatus A, through the 110

- usual pipe connections a , a' . Heretofore the feed water for the boiler B, has been pumped into the lower portion of said boiler B, through the pipe a' , a T connection a^2 , being provided for the pipe leading to the pump mechanism and a check valve a^3 , being also provided in said pipe a' , to protect the pressure apparatus A, against back pressure.
- 10 The boiler B, is provided with the usual water gauge b , and pressure indicator b' , and is connected with the feed water tank F, through the medium of an upper pipe c , and a lower pipe c' , the latter being provided 15 with a check valve c'' , as shown in Fig 1, and communicating with a stand pipe f , which in turn communicates with the lower portion of said feed water tank F, through the medium of the valve f^2 . In a similar 20 manner the upper feed pipe c , communicates with the upper part of the feed water tank F, through the medium of a valve f' , as will be understood more particularly by reference to Fig. 3, of the drawings, by reference 25 to which it will also be seen that an auxiliary by-pass pipe d , connects the upper pipe c , (indirectly through the stand pipe f) with the lower pipe c' ,—said auxiliary by-pass pipe d , functioning as a heating means 30 upon occasion, for the feed water introduced into the tank F, as hereinafter set forth. Said auxiliary heating pipe d , is provided with a valve d' , by means of which communication therethrough may be 35 opened, closed or regulated.

n , is a nozzle projecting into the upper part of the tank F, for the introduction thereinto of fresh water, said nozzle n , being the termination of the feed and of the water 40 pipe n' , which is connected with any suitable source of water supply under pressure as may be found most expedient according to circumstances of installation of the plant, considered in a unitary sense. The nozzle 45 n , has a constricted discharge, so as to spray the water supply as introduced into the upper portion of the tank F, in such manner as to facilitate the condensation of any steam that may be present therein, and 50 also to obviate the "knocking" noise incidental to the introduction of cold water into the tank, which is relatively hot under normal conditions of use.

The check valve c'' , introduced in the 55 lower pipe c' , between the boiler B, and the feed water heater tank F, prevents back pressure during the feed to the boiler B; and the latter is provided with a pet cock f^{22} , communicating with the upper portion 60 thereof as shown particularly in Fig. 3, for the relief of internal pressure or tension upon occasion, as the case may be.

The valves f' , and f^2 , are actuated and controlled simultaneously through the medium 65 of a common coupling bar e , with which

their stems are connected as hereinafter set forth. This coupling rod e , extends vertically in parallelism with the vertical axis of the tank F, as seen in Figs. 1 and 2, and is supported medially on a screw stud s , 70 rigidly affixed to the side of the tank F, as shown in Fig. 2, and in detail in Fig. 6, by reference to which latter it will be seen that said screw s , engages with a rotatable nut i , provided with a gear wheel i' , and that the 75 said coupling bar e , is held and positioned on said rotatable nut i , by and between an annular shoulder i^2 , and a jam nut i^3 , thereon, as shown in detail in the aforesaid Fig. 6, of the drawings. As a result, it is obvious 80 that, as the nut is rotated on the said stationary screw s , the coupling bar e , will be advanced or retracted with relation to the tank F, thereby opening or closing the valves f' , f^2 , as the case may be. In Figs. 1, 2, 85 4 and 6, of the drawings, the coupling bar e , is shown in retracted position, in which the valves f' , f^2 , are closed. g , g , are guide posts protuberant from the adjacent side of the tank, which guide posts extend through holes formed for the purpose in the coupling bar e , and thereby maintain the alignment and contribute to the support of said coupling bar. They also afford means for the provision of shoulders g' , g^2 , which limit 90 and prescribe the extent of movement of said coupling bar e . j , j , are balance springs which tend to steady the ends of the coupling bar e , and to hold the latter against the stops g^2 , representing the closed position of the valves f' , f^2 .

Fig. 5, shows in detail the connection between the valve stems of the valves f' , f^2 , and the coupling bar e , the same being identical for each. That is to say, the outer end of the stem f^* , of each valve is screw threaded and extends through a hole e' , made for the purpose in the coupling bar e , and is capped by a nut f^3 , which forms the outer bearing against said coupling bar e , the bearing on the other or inner side thereof being afforded by a spring f^4 , interposed between said coupling bar e , and an adjustable collar f^5 , on said threaded portion of the valve stem f^* ,—this construction holding the parts involved in operative relationship, and providing means for compensation of wear, etc.

The coupling bar e , is also connected positively with the stem n^2 , of the valve n^3 , which is interposed in the feed water supply pipe n , the latter being positioned on the side of said coupling bar e , opposite to that on which the aforesaid valves f' , f^2 , are situated, so that when the said valves f' , f^2 , are open the water supply valve n^3 , is closed, and vice versa, as the case may be,—all three of said valves being actuated simultaneously through the medium of the rotatable nut i , and the coupling bar e , common to all. Hence, the feed water supply through the 130

pipe n' , and nozzle n , to the tank F, is shut off while the latter is replenishing the boiler B, with pre-heated water to maintain approximately the prescribed operative water 5 level therein and conversely, when the valves f' , f^2 , are closed, the valve n^3 , is open and supplies fresh water to the tank F,—the latter being filled, and maintained so under normal conditions. To effect the pre-heating 10 of the feed water in the tank F, the valve d' , is opened, admitting live steam from the boiler B, to and through the radiator pipe d .

The foregoing description, both as relates to construction and operation of parts and 15 appurtenances, is identical with that of our aforesaid concurrent application Serial No. 534,818, excepting that in the present case the gear i' , is substituted for the crank arm on the rotatable nut i ,—the distinctive feature of my present invention being the actuation of the coupling bar e , automatically through the medium of an electric motor, the operation of which is controlled by 20 means of a float L, governed by the water level in the boiler B,—a gear m , on the motor shaft meshing with the gear i' , on the rotatable nut i , and the contactual surfaces of both gears being of sufficient extent to compensate for the movement of the 25 nut gear i' , upon and as related to the gear m , of the motor M which latter is fixed in position. Thus, obviously, the advance or retraction of the coupling bar e , will depend 30 on the direction of rotation of the motor 35 shaft.

Obviously the electric switch actuating float L, might be positioned in the boiler B, and provided with extraneous connections, but I prefer to install it within an exterior 40 cylindrical chamber B', which may communicate with the interior of the boiler B, through the medium of a pipe b' , connected with the water gauge b , as indicated more particularly in Figs. 1 and 7 of the drawings 45 so that the water level, in said float chamber B', will correspond with that in the boiler B, and gauge b .

The float L, is provided with a toothed rack l , for engagement with a pinion r , affixed 50 to a rock shaft r' , mounted in bearings b^2 , b^2 , in the side walls of the float chamber B', as shown more particularly in Fig. 8, of the drawings. This rock shaft r' , has rigidly attached to one of its outer extremities a 55 rocker arm r^2 , which is connected with a duplicate thrust knife plate switch S, of a standard type, the terminals s , s , which are connected with the main or power line wires p , p , and with the electric motor circuit 60 m' , m' , in a manner well known in the art. Hence, when the water in the boiler falls 65 below a prescribed level the sinking of the float L, will cause the rack l , to rotate the pinion r , sufficiently to make the arm r^2 , close the switch S, in such manner as to ro-

tate the motor M, in a direction to effect the retraction of the coupling bar e , thereby closing the supply valve n^3 , to the tank F, and opening the said valves f' , f^2 , to the boiler B. The raising of the normal water 70 level to that prescribed causes the float L, to reverse this action through the medium of the switch S, resulting in the reversal of direction of motion of the motor M, and the closing of the valves f' , f^2 , and opening of 75 the valve n^3 .

The electric switch S, is, of course, timed to open the circuit at the completion of each operation, but in order to guard against failure of the switch or float mechanism in 80 this respect, the coupler bar e , may be included in the electric circuit when said coupling bar e , is in normal medial position.

From the foregoing it will be seen that I 85 attain an absolute automatic feed system for the boiler of a cloth steaming and pressing apparatus which is simple, positive and safe, and in which the necessity for manual labor or supervision is eliminated, in that even possible failure or disarrangement of the 90 float mechanism and electric switch could not result disastrously, since the valve coupling bar itself acts as a safety switch to limit the extent of rotative motion of the electric motor in either direction. 95

What I claim as my invention and desire to secure by Letters Patent is:—

1. A water feeding device for connection with a cloth steaming and pressing apparatus, comprising a boiler, a water tank, pipes connecting the top and bottom portions of said boiler and tank, a valve in each of said pipes, a water supply pipe connecting with said tank, a valve in said water supply pipe, and means for simultaneously 100 operating said valves consisting of a coupling bar connected therewith, an electric motor for actuating said coupling bar, and a float governed by the water level in the boiler and arranged to control the electric 105 circuit in which said electric motor is interposed, substantially in the manner and for the purpose set forth.

2. A water feeding device for connection with a cloth steaming and pressing apparatus, comprising a boiler, a water tank, pipes connecting the top and bottom portions of said boiler and tank, a valve in each of said pipes, a water supply pipe connected with said tank, a valve in said water supply 115 pipe, and float-controlled electrical means for simultaneously opening and closing said valves, substantially in the manner and for the purpose set forth.

3. A water feeding device for connection with a cloth steaming and pressing apparatus, comprising a boiler, a water tank, pipes connecting the top and bottom portions of said boiler and tank, a valve in each of said pipes, a water supply pipe connected with 120 125

said tank, a valve in said water supply pipe, means for simultaneously operating said valves, consisting of a coupling bar connected therewith, a travelling nut connected with 5 said coupling bar, a gear on said travelling nut, an electric motor having a gear meshing with said gear on the travelling nut, and float means controlled by the water level in the boiler and controlling the electric current in which the motor is interposed, substantially in the manner and for the purpose set forth.

4. A water feeding device for connection with a cloth steaming and pressing apparatus, comprising a boiler, a water tank, pipes connecting the top and bottom portions of said boiler and tank, a valve in each of said pipes, a water supply pipe connected with said tank, a valve in said water supply pipe, 15 means for simultaneously operating said valves consisting of a coupling bar whereby the main water supply to the tank is shut off when the valves to the boiler are open and vice versa, an electric motor arranged 20 to actuate said coupling bar, and a float controlled by the water level in the boiler and governing the electric current in which said motor is interposed, substantially in the manner and for the purpose set forth.

5. A water feeding device for connection with a cloth steaming and pressing apparatus, comprising a boiler, a water tank, pipes connecting the top and bottom portions of said boiler and tank, a valve in each of said 35 pipes, a water supply pipe connected with said tank, a valve in said water supply pipe, means for simultaneously operating said valves consisting of a coupling bar whereby the main water supply to the tank is shut off when the said valves to the boiler are open, and vice versa, an electric motor arranged to actuate said coupling bar, a float controlled by the water level in the boiler, a rack mounted on said float, a pinion meshing with said rack, and switch mechanism 40 connected with said pinion and controlling the electric circuit in which the motor is interposed, substantially in the manner and for the purpose set forth.

terposed, substantially in the manner and for the purpose set forth.

6. A water feeding device for connection 50 with a cloth steaming and pressing apparatus, comprising a boiler, a water tank, pipes connecting the top and bottom portions of said boiler and tank, a valve in each of said pipes, a water supply pipe connected with said tank, a valve in said water supply pipe, means for simultaneously operating said valves, consisting of a coupling bar whereby the main water supply to the tank is shut off when the said valves to the 60 boiler are open, and vice versa, an electric motor arranged to actuate said coupling bar, a float chamber connected with the boiler, a float therein actuated by the water level in the boiler, a rack mounted on said float, 65 a pinion meshing with said rack, and switch mechanism connected with said pinion and controlling the electric circuit in which the motor is interposed, substantially in the manner and for the purpose set forth.

7. A water feeding device for connection 70 with a cloth steaming and pressing apparatus, comprising a boiler, a water tank, pipes connecting the top and bottom portions of said boiler and tank, a valve in each of said pipes, a water supply pipe connected with said tank, a valve in said water supply pipe, means for simultaneously operating said valves, consisting of a coupling bar whereby the main water supply to the tank is shut off 75 when the said valves to the boiler are open, and vice versa, an electric motor arranged to actuate said coupling bar, a float controlled by the water level in the boiler and governing the electric circuit in which said motor is interposed, and electric circuit opening devices on said coupling bar for prescribing the extent of motion in either direction, substantially in the manner and for the purpose set forth.
